TOY FRYING PAN

Silas M. Ford, St. Paul, Minn.

Application February 18, 1957, Serial No. 44,906

Term of patent 14 years

(Cl. D34—15)

Figure 1 is a perspective view of a toy frying pan, showing my new design;

Figure 2 is a top plan view of the same;

Figure 3 is a side elevational view of the same; and

Figure 4 is a side elevational view of one of the removable blocks used in conjunction therewith.

I claim:

The ornamental design for a toy frying pan, as shown.
